RAILWAY LIGHTING SYSTEM.

1,417,787.

Specification of Letters Patent. Patented May 30, 1922.

Application filed January 29, 1916. Serial No. 74,999.

To all whom it may concern:

Be it known that I, LEONARD A. WATSON, a citizen of the United States, residing at Port Washington, L. I., in the county of 5 Nassau and State of New York, have invented certain new and useful Improvements in Railway Lighting Systems, of which the following is a full, clear, and exact description, such as will enable others skilled in the 10 art to which it appertains to make and use the same.

This invention relates to railway lighting systems, and more particularly to the automatic regulation of axle driven car lighting 15 generators employed to supply current to a translating lamp circuit and to a storage battery associated in the system as a reservoir of current to supply the lamps when, for example, the train speed is below that 20 at which the generator is designed to carry the load.

One of the objects of the invention is to provide simplified and improved controlling means to govern the generator in accordance with the state of battery charge.

Further objects are to simplify the character of the generator controller, to reduce the factors employed in the control, and to provide reliable protection and operation of 0 the various elements of the system at all times.

Other objects will be in part obvious and in part noted hereinafter in connection with the description of the accompanying drawing, which illustrates diagrammatically an exemplary embodiment of the invention.

It is customary in car lighting systems to provide a generator driven by the car axle and having a shunt field winding with a 0 regulating resistance in the field circuit, together with an automatic switch in the main circuit designed to connect the generator with the load when the voltage of the generator attains a value for efficient current 5 delivery.

In the drawing there is shown a generator G having a shunt field F with a carbon pile resistance C serially included in the field circuit. The carbon pile is of a character to vary its resistance in accordance with the variation in pressure of the contacting carbons, which pressure is governed by a bell crank lever 1 pivoted and normally biased either by a spring or by gravity to compress the carbons to a minimum resistance value.

A main switch 2 is positioned in one of the lines between the generator and the battery and is automatically controlled by a shunt coil 3, the strength of which insures an open circuit when the train speed is below a pre-determined rate, for example, fifteen miles 60 an hour. A battery B and lamps L are connected in parallel circuits across the generator mains 4 and 5.

A voltage coil 6, comprising the winding 65 of a solenoid having a magnetic core 7 attached to the long arm of the bell crank lever 1, constitutes the electro-magnetic controlling means for effecting the generator regulation. This coil 6 is connected by line 70 8 to one generator main and through adjustable resistance R arranged in steps 9 and 10 by line 11 to the other generator main. An ampere hour meter M or other mechanism which quantitatively measures the charge 75 and discharge of current to or from the battery, or other suitable electro-mechanical or electrical device which is affected by condition of the battery with respect to the available stored current therein, is employed to 80 control the resistance R in the circuit of the voltage coil in such manner as to alter the setting of the latter in accordance with the condition of the battery charge, and accordingly to determine the degree of responsiveness 85 of the voltage coil and voltage of the generator to be maintained. By thus altering the resistance in the circuit of coil 6 the effective resistance per mean turn of the coil is altered and the number of ampere turns 90 for a given voltage is changed. For example, with increased effective resistance per mean turn a higher voltage is required to restore the pull of the coil to normal.

The meter M may be provided with a suitable armature and with a field winding MF in the battery circuit so connected that the current to the battery operates the meter in one direction, and current from the battery operates the meter in the reverse direction. 95 While the generator is supplying current to the battery and lamps simultaneously, it will be noted that the meter operates in response only to that portion of the current delivered to the battery.

When a generator controlled only to deliver current at constant voltage is employed to charge a storage battery, there tends to result an injurious initial inrush of current if the battery is depleted, and the current 110

tends thereafter to taper during the charge for inherent protection of the battery against over-charge. In order to prevent such injurious inrush of current and to regulate more efficiently the charging rate, there is provided an element of resistance 13 in series with the battery circuit when the battery is largely discharged, which resistance tends to limit the amperage of the current traversing the circuit and thereby to limit the initial inrush to the battery.

The meter M is also provided with suitable contacts, illustrated schematically, whereby suitable circuits are established by the movable meter pointer 14 in accordance with its position indicative of the instant battery charge. As illustrated, the meter pointer is provided with a contact 15 and a separate insulated contact 16, the former of which engages with a segmental contact 17 while the condition of the battery charge is below a predetermined point. During this condition there is a circuit established across the contacts 15 and 17 extending from the voltage coil 6 by line 18 through the meter by line 19 to the opposite side of the resistance R, thereby shunting said resistance and rendering the voltage coil 6 of maximum responsiveness, for example to maintain 35 volts. During an initial portion of this time the battery resistance 13 is included in circuit so that the effect of this resistance in addition to the setting of the voltage coil insures proper charging rate to the battery. After the meter has operated to indicate that the battery has become partially charged, the pointer contact 16 engages the segmental meter contact 20 and establishes a shunt circuit thereacross about the battery resistance 13, so that thereafter all of the voltage of the generator is applied to the battery. After (or before or simultaneously with, as desired) this removal of the battery resistance, the pointer contact 15 travels to leave the meter contact 17 and engages a second segmental contact 21, which restores section 10 of the resistance R in circuit with the voltage coil, but still short-circuits section 9 of such resistance. Under these conditions the setting of the voltage coil is altered to a lesser degree of responsiveness, for example to maintain 40 volts. As the battery reaches fully charged condition the meter contact 15 is moved further to leave contact 21 and engages a third contact 22, which again short-circuits all the resistance R from the circuit of the voltage coil, thereby again altering its setting to 35 volts or floating battery value. The voltage of the battery has then risen to a point where the charging current is automatically reduced to safe confines. If desired, however, the pointer contact 16 may be arranged (as shown) to leave engagement with the meter contact 20 at this time and thus reinsert battery resistance

13 in the battery circuit, thereby effectually terminating charging and practically isolating the battery. When the battery is thus fully charged the voltage coil maintains uniform voltage of the generator, the current being determined in accordance with the load.

During discharge of the battery, when the train is at rest or below critical speed, the meter travels backward to reverse the sequence of circuits set forth, and insure the proper character of generator control when the generator resumes action. In order to prevent useless consumption of current by the battery resistance 13 when the battery is supplying current to the lamps, there are provided back contacts 23 on the main switch 2 connected to a shunt circuit by lines 24 and 25 to cut out the battery resistance when the main switch is opened. This is in addition to the battery resistance shunt circuit established by the meter contacts within narrower limits between full and depleted battery.

The meter M is shown schematically as establishing direct contact by its movable pointer and contact segments for the various circuits described. It will be understood, however, that the meter may be constructed as desired, either to make and break circuit directly, or through the medium of suitable telegraphic relays, in order to reduce the value of the currents controlled by the meter pointer. It will further be understood that the meter is provided with resetting means to establish synchronism with the state of battery charge, and also with automatic means to compensate for internal battery losses.

The voltage coil 6 is permanently connected in circuit to effect the regulation throughout the operation of the system, the character of the regulation being automatically proportioned to the condition of the battery charge. In case of breakage of a battery lead, it will further be seen that the voltage control is still maintained to govern the generator. The sections 9 and 10 of the resistance R of the circuit of the voltage coil may be adjustable, and the time, and sequence of the shunt circuits about these resistance sections may be altered as desired by mechanical alteration of the meter.

Having described my invention, what I claim as new and desire to secure by Letters Patent is:

1. In a railway car lighting system, in combination; a variable speed generator; a storage battery connected to be charged thereby; regulating means, responsive to a function of the generator output, operable to maintain the generator voltage constant; and means responsive to the condition of charge of the battery arranged to affect said regulating means to maintain a higher con-

- stant generator voltage when the battery has reached a predetermined state of charge.
2. In a railway car lighting system in combination; a variable speed generator; a storage battery connected to be charged thereby; regulating means, responsive to a function of the generator output, operable to maintain the generator voltage constant; and means responsive to the condition of charge of the battery arranged to cause said regulating means to maintain a depressed generator voltage constancy at the beginning of charging, a raised generator voltage constancy during the major period of charging and a depressed generator voltage constancy after the charging is completed.
3. In a railway car lighting system, in combination, a variable speed generator having a shunt field, a storage battery adapted for connection across the generator mains, an ampere hour meter constructed and connected to substantially synchronize with the quantity of battery charge, a resistance connected in the battery circuit adapted to limit the charging current, and connections whereby said resistance is rendered relatively more effective by said meter during predetermined initial battery charging and relatively less effective during a subsequent period of battery charging.
4. In a railway car lighting system, in combination, a variable speed generator, a storage battery adapted for connection therewith, an ampere hour meter constructed and connected to substantially synchronize with the quantity of battery charge, means in the battery circuit adapted to limit the charging current, and connections whereby said means is controlled by said meter and is rendered relatively more effective by the latter at the beginning and end of battery charging and relatively less effective during an intermediate period of battery charging.
5. In a railway car lighting system, in combination, a variable speed generator having a shunt field, a storage battery adapted for connection across the generator mains, an ampere hour meter constructed and connected to substantially synchronize with the quantity of battery charge, a resistance connected in the battery circuit adapted to limit the charging current, and connections whereby said resistance is rendered effective by said meter at the beginning and end of battery charging and is rendered ineffective by said meter during an intermediate period of charging.
6. In a railway car lighting system, in combination, a variable speed generator, voltage responsive means to regulate said generator while running above a predetermined speed, a storage battery adapted for connection with said generator, means operable by the battery charging and discharging current to substantially synchronize with the quantity of battery charge, a fixed resistance in the battery circuit to limit the charging current and connections whereby said resistance is rendered effective by said second-mentioned means during a predetermined initial period of battery charging to depress the charging current at the maintained generator voltage.
7. In a railway car lighting system, in combination, a variable speed generator, regulating means therefor, a storage battery adapted for connection with said generator, and automatic means for causing said regulating means to depress the generator voltage to one standard of constancy during a predetermined initial period of charging and to raise the generator voltage to another standard of constancy during a subsequent predetermined period of charging.
8. In a railway car lighting system, in combination, a variable speed generator, regulating means therefor, a storage battery adapted for connection with said generator, automatic means for causing said regulating means to depress the generator voltage during an initial period of charging, to restore full voltage during another period of charging and again to depress the voltage at the end of charging.
9. In a railway car lighting system, in combination, a variable speed generator, voltage responsive regulating means therefor, a storage battery adapted for connection with said generator, means operable by the battery charging and discharging current and substantially synchronizing with the quantity of battery charge, and means controlled by said second-mentioned means and controlling said first-mentioned means to depress the generator voltage to one standard of constancy during a predetermined initial period of battery charging and to raise the generator voltage to another standard of constancy during a subsequent predetermined period of battery charging.
10. In a railway car lighting system, in combination, a variable speed generator, voltage responsive regulating means therefor, a storage battery adapted for connection with said generator, means operable by the battery charging and discharging current and substantially synchronizing with the quantity of battery charge, and means controlled by said second-mentioned means and controlling said first-mentioned means to depress the generator voltage during a predetermined initial period of battery charging, to restore full voltage during a predetermined subsequent period of battery charging, and again to depress the voltage when the charge is complete.
11. In a railway car lighting system, in combination, a variable speed generator, a storage battery adapted for connection therewith, and automatic regulating means

responsive to a function of the generator output and to the condition of charge of the battery adapted to maintain one generator voltage constancy during an initial period of battery charging and another higher generator voltage constancy during a subsequent period of battery charging.

12. In a railway car lighting system, in combination, a variable speed generator, a storage battery adapted for connection therewith, and automatic regulating means to maintain a depressed generator voltage constancy during an initial period of battery charging, an increased generator voltage constancy during a subsequent period of battery charging, and a depressed generator voltage constancy at the end of battery charging.

13. In a railway car lighting system, in combination, a variable speed generator; a storage battery adapted for connection therewith; voltage responsive regulating means for said generator; and means, including an ampere hour meter adapted to substantially synchronize with the quantity of battery charge, whereby said regulating means maintains one predetermined generator voltage constancy during a predetermined initial period of battery charging and another higher predetermined voltage constancy during a subsequent period of battery charging.

14. The herein described method of controlling an electric car lighting system including a variable speed generator and a battery, which consists in maintaining a depressed generator voltage constancy during an initial period of battery charging and thereafter in maintaining an increased generator voltage constancy until the battery charge is completed.

15. In a railway car lighting system, in combination, a variable speed generator; automatic regulating means therefor; a storage battery adapted for connection across the generator mains; means, independent of said regulating means, adapted to affect the battery charging current; and common means for governing the action of said first-mentioned means and said second-mentioned means.

16. In a railway car lighting system, in combination, a variable speed generator; automatic regulating means therefor; a storage battery adapted for connection across the generator mains; means adapted to limit the battery charging current independently of said regulating means; and means, including an ampere hour meter constructed and connected to substantially synchronize with

the quantity of battery charge, to determine the character of regulation to be effected by said regulating means and to govern the effectiveness of said second-mentioned means.

65

17. In a railway car lighting system, in combination, a variable speed shunt wound generator, voltage responsive regulating means therefor, a storage battery adapted for connection across the generator mains, a resistance connected in the battery circuit to limit the charging current, and means to determine the voltage to be maintained by said regulating means and to govern the effectiveness of said resistance.

70

18. In a railway car lighting system, in combination, a variable speed generator; automatic regulating means therefor, including a voltage coil connected across the generator mains; a storage battery adapted for connection across the generator mains; a resistance connected in the battery circuit to limit the charging current; means to vary the resistance per mean turn of said voltage coil; and means controlling said last-mentioned means and said battery circuit resistance to decrease the resistance per mean turn of said voltage coil and render said battery circuit resistance effective at the beginning of charge, and to increase the resistance per mean turn of said voltage coil and render said battery circuit resistance ineffective during a subsequent period of battery charge.

75

19. The herein described method of controlling car lighting systems which consists in positively limiting the initial charging current to the battery, when depleted, substantially independently of the generator regulation and thereafter governing the charging current solely by regulating the generator voltage.

80

20. In an electrical system of distribution, in combination, a variable speed generator and battery adapted to be charged thereby, an external regulator for said generator including electro-responsive means to maintain the generator output substantially constant in spite of speed changes, and means automatically operative at an interval during the period from low to full battery charge and indicative only of battery conditions for establishing the standard of regulation to be maintained by said regulator for a succeeding period of charge prior to full battery charge.
